UNITED STATES PATENT OFFICE.

LYMAN D. MINOR, OF NEW YORK, N. Y., ASSIGNEE OF ONE-HALF TO JOHN P. LINDSAY, OF SAME PLACE.

GARMENT-CLASP.

SPECIFICATION forming part of Letters Patent No. 272,075, dated February 13, 1883.

Application filed November 14, 1882. (No model.)

To all whom it may concern:

Be it known that I, LYMAN D. MINOR, a citizen of the United States, residing at New York, in the county of New York and State of New York, have invented a new and useful Garment-Clasp, of which the following is a specification, reference being had to the accompanying drawings.

This invention relates to that class of garment-clasps which comprise two spring-actuated clamping-jaws, only one of which is secured to its retaining fabric, while the rear edge of the other lever-jaw projects out and is unprotected. This projecting edge of the lever-jaw, in this class of garment-clasps as heretofore constructed, is a cause of much annoyance to the wearer. The apparel is constantly catching against it, and frequently becomes torn, while this tangling of the apparel with the projecting edge of the jaw sometimes damages the clasp.

To obviate all these disadvantages is the object of my present invention, which is designed to provide a simple, durable, inexpensive, and efficient clasp, in which the surface of either and both jaws will present a smooth contact with the apparel, and in which there will be no projecting edges to engage or tear the apparel.

To this end the invention consists substantially in forming the clamping-jaws alike and connecting them both at their rear edges to the retaining fabric, one of the jaws being provided with a hinge-joint in rear of its pivot, all as will be hereinafter more fully specified.

In the drawings, Figure 1 is a perspective view of my improved clasp attached to its retaining fabric. Fig. 2 is a side view thereof. Fig. 3 is a longitudinal sectional view. Fig. 4 is a transverse sectional view.

Referring to the drawings, A A' designate

the two clamping-jaws, which are substantially alike, both being provided with engaging teeth or serrations a at their front clamping-edges, and pivoted together in rear of the teeth, as at a' , an actuating-spring, B, being interposed to force the clamping-edges of the jaws together. At their rear ends, a^2 , both jaws are secured to the retaining fabric C.

D designates a joint formed in one of the jaws, A', between its secured end a^2 and its pivot a' . This joint D may be formed in any suitable manner, but is preferably constructed, as shown in the drawings, by turning over the edges of the jaw at the joint to form eyes a^3 , through which passes a transverse pin, E, or its equivalent. By pressing at the joint D the clamping ends of the jaws will separate, as shown in dotted lines, Fig. 2, to clasp the garment in the usual manner.

The advantages of my invention will be readily understood and appreciated. The ready and sure operation of the jaws is increased, as greater bearing-surface for the thumb is provided at the joint D than heretofore, and there are no projecting edges to be engaged by the apparel.

I claim as my invention—

As an improved article of manufacture, a garment-clasp comprising two clamping-jaws pivoted together, each jaw having a rear end to be engaged by the retaining fabric, and one jaw being formed with a hinge-joint in rear of its pivot, as and for the purpose set forth.

In testimony that I claim the foregoing as my own I have hereto affixed my signature in presence of two witnesses.

LYMAN D. MINOR.
